UNITED STATES PATENT OFFICE.

ALBERT SCHWENKE, OF HOUSTON, TEXAS.

DESIGN FOR A CHILD'S QUAKER BONNET.

45,076.

Specification for Design.

Patented Dec. 23, 1913.

Application filed September 26, 1913. Serial No. 792,045. Term of patent 3½ years.

To all whom it may concern:

Be it known that I, ALBERT SCHWENKE, a citizen of Germany, residing at Houston, in the county of Harris and State of Texas, have invented a new, original, and ornamental Design of a Child's Quaker Bonnet, of which the following is a specification, reference being had to the accompanying drawing, forming a part thereof.

Figure 1 is a top plan view of a bonnet illustrating my new design; Fig. 2 is a front view thereof; and Fig. 3 is a side elevation.

The child's Quaker bonnet is manufactured out of the coarse fibered loofah.

I claim—

The ornamental design for a child's Quaker bonnet as shown.

ALBERT SCHWENKE.
